PACKAGE FORMING MACHINE

Robert H. Ganz, Bergenfield, N.J., assignor to Continental Can Company, Inc., New York, N.Y., a corporation of New York

Filed May 31, 1962, Ser. No. 198,974

27 Claims. (Cl. 53—48)

This invention relates in general to new and useful improvements in machines for forming packages, and more particularly relates to a machine for combining a plurality of members into a package utilizing a package forming member.

In accordance with the spirit of this invention, it is proposed to supply members in a single line, then to separate the members into individual groups, after which a blank is applied to each group of the members and the blank is interlocked with the members and then folded in a manner so as to retain the interlock with the members so that the blank, when folded, combines with the members to form a unitary package.

In accordance with the foregoing basic concept of the invention, it is an object of this invention to provide a novel apparatus which will automatically supply a blank to a group of members disposed in a single row with the blank being aligned with the members while the members constantly move, after which a central portion of the blank is forced down over the upper end of the members and interlocked therewith to complete a first step in the securing together of the members to form a unitary package which may be readily handled and from which the members may be easily removed.

This invention particularly relates to a package which is formed of a plurality of cans or other containers having peripheral projections at the upper ends thereof, and which containers are connected together in a package by means of a generally trough-shaped member, the trough-shaped member being foldable from a flat blank which has notches in central portions thereof corresponding to the spacing of the containers and which notches receive the peripheral projections of the containers to form an interlock therewith, the machine including blank folding blades which are automatically moved downwardly alongside the containers to force the central portion of a blank into interlocked engagement with the containers, the folding blades being mounted for movement with the containers during the engagement of the folding blades with the blank so that the proper seating and interlocking of the blank with respect to the containers is assured by the folding blades.

Another object of this invention is to provide a package forming machine into which cans and similar containers are continuously fed, the machine being provided with conveyor means for moving the cans in predetermined groups which are slightly spaced from one another, means for automatically supplying blanks to the groups of cans in timed relation to the movement thereof, and other means for interlocking the blanks with the cans and then folding the blank to form a complete package forming member which is interlocked with the cans and together therewith forms a package.

Another object of this invention is to provide novel blank folding means which forms a flat blank into two interlocked troughs and interlocks the free edges of the blank, the folding means including folding blades for first

2

folding intermediate portions, of the blank down around the sides of a row of cans, other folding means for progressively folding remote edge portions of the blank into overlapping relation and simultaneously folding projecting locking tabs out of the plane of one of the edge portions and into alignment with slits in the other of the edge portions, and further means for forcing the locking tabs through the slits to assure the interlocking of the edge portions.

Still another object of this invention is to provide a novel conveyor for receiving a continuous supply of cans disposed in a row and continuously moving such cans in groups of a predetermined number, the conveyor including endless members having can pushers carried thereby, and the can pushers defining the groups of cans which are to be delivered and acting as separators between adjacent groups of cans.

A further object of this invention is to provide novel locking tab folding means for simultaneously folding locking tabs disposed along the edge of an edge portion of a blank into a plane disposed normal to the plane of the edge portion simultaneous with the swinging of the edge portion, whereby as the edge portion is brought down into overlying relation with respect to another edge portion of the blank, the locking tabs are automatically positioned for passage through slits in the other edge portion.

A still further object of this invention is to provide novel means for seating a blank on a plurality of cans disposed in a row and initially interlocking the blank with the peripheral projections at the ends of the cans defined by the seams thereof, the blank folding means including two spaced apart blank supports disposed on opposite sides of the path of movement of the cans, and a pair of blank folding blades movable downwardly alongside the cans and intermediate the cans and the blank support whereby as the folding blades move down alongside the cans, the folding blades will draw a central portion of a blank tight around the cans and in cooperation with the cans and the blank supports will reversely fold intermediate portions of the blank along the sides of the cans.

Yet another object of this invention is to provide an automatic and continuously operating machine which will automatically position a blank with respect to a group of cans disposed in a single row, the cans having been automatically arranged in the group by the machine and then first interlocking the blank with the cans, after which the blank is folded into a double nested configuration, with the edge portions thereof interlocked so as to define a package forming member which, together with the cans, defines a readily handled package, the operation of the machine being entirely automatic and continuous and requiring no manual operations whatsoever.

With the above and other objects in view that will hereinafter appear, the nature of the invention will be more clearly understood by reference to the following detailed description, the appended claims and the several views illustrated in the accompany drawings:

In the drawings:

FIGURES 1 and 1-A are plan views of the machine, and show the specific arrangements of the components thereof.

FIGURE 2 is a longitudinal vertical sectional view taken along the line 2—2 of FIGURE 1, and shows further the structural details of a portion of the machine.

FIGURE 2-A is a longitudinal vertical sectional view

taken along the line 2-A—2-A of FIGURE 1-A, and shows further the details of the remainder of the machine.

FIGURE 2-B is a schematic elevational view showing the manner in which blanks are supplied to the blank conveying means of the machine.

FIGURE 3 is a schematic perspective view showing generally the details of the drive mechanism of the machine.

FIGURE 4 is an enlarged transverse vertical sectional view taken along the line 4—4 of FIGURE 2, and shows more specifically the details of the drive of the machine, and the manner in which the blanks and the cans are fed thereby.

FIGURE 5 is a fragmentary longitudinal vertical sectional view taken along the line 5—5 of FIGURE 1, but shows the apparatus in position as a blank is being fed to a group of cans.

FIGURE 6 is an enlarged fragmentary longitudinal vertical sectional view similar to FIGURE 5 and shows the blank folding apparatus in a further step beyond that of FIGURE 5, the view being taken along the line 6—6 of FIGURE 9.

FIGURE 7 is another longitudinal vertical sectional view similar to FIGURE 5, and shows a further position of the blank folding blades during the blank folding operation.

FIGURE 8 is a transverse vertical sectional view taken along the line 8—8 of FIGURE 1, and shows the blank folding blades immediately prior to the engagement thereof with a horizontally-positioned blank.

FIGURE 9 is a transverse vertical sectional view similar to FIGURE 8 and shows a step in the blank folding operation after that shown in FIGURE 8, with the blank being folded down around the upper portions of the cans and interlocked therewith.

FIGURE 9-A is an enlarged fragmentary transverse vertical sectional view showing a portion of the apparatus of FIGURE 9 and more specifically the manner in which the blank is folded and engaged with the cans.

FIGURE 10 is an enlarged fragmentary horizontal sectional view taken along the line 10—10 of FIGURE 6, and shows more specifically the mounting and driving arrangement of the blank folding blades.

FIGURE 11 is a schematic fragmentary vertical sectional view taken along the line 11—11 of FIGURE 10, and shows the specific drive of the blank folding blades.

FIGURE 12 is an enlarged fragmentary vertical sectional view taken along the line 12—12 of FIGURE 1, and shows the means for limiting the clockwise swinging of one of the support arms for the blank folding blades.

FIGURE 13 is a fragmentary enlarged longitudinal vertical sectional view similar to FIGURE 12 and shows modified means for limiting the pivoting of the support arms of FIGURE 5.

FIGURE 14 is an enlarged fragmentary vertical sectional view taken along the line 14—14 of FIGURE 1-A and shows the specific details of folding blades for folding the locking tabs of the blanks.

FIGURE 15 is an enlarged fragmentary elevational view of the forward portion of the folding blades of FIGURE 14 and shows a blank edge and one of the locking tabs thereof engaged with the folding blades.

FIGURE 16 is an enlarged fragmentary plan view of the folding blades and the blank of FIGURE 15 and shows further the specific relationship of the blank with respect to the folding blades.

FIGURE 17 is a plan view similar to FIGURE 16 and shows the blank in an advanced position with respect to the folding blades with an initial folding of one of the locking tabs having results.

FIGURE 18 is a fragmentary vertical sectional view taken along the line 18—18 of FIGURE 17 and shows the manner in which the locking tab is specifically engaged by the folding blades.

FIGURE 19 is an enlarged elevational view of the folding blades of FIGURE 14 and shows a blank more fully engaged therewith, one of the locking tabs of the blank having been downwardly folded while the next following locking tab is just coming into engagement with the folding blades.

FIGURE 20 is an exploded perspective view of the folding blades of FIGURE 14, and shows the general details thereof.

FIGURE 21 is an enlarged fragmentary transverse vertical sectional view taken along the line 21—21 of FIGURE 1-A and shows the details of the rollers for folding the edge portions of the blank towards overlapped relation.

FIGURE 22 is a fragmentary transverse vertical sectional view taken along the line 22—22 of FIGURE 1-A and shows a further folded position of the uppermost edge portion of the blank and the initial engagement thereof with the locking tab folding blade.

FIGURE 23 is an enlarged fragmentary transverse vertical sectional view taken along the line 23—23 of FIGURE 1-A and shows a further folded position of the edge portions of the blank, with the view being taken through one of the locking tabs of the blank and shows the locking tab in a horizontal position.

FIGURE 24 is an enlarged fragmentary transverse vertical sectional view taken along the line 24—24 of FIGURE 1-A and shows a further folded position of the locking tabs to a vertical position.

FIGURE 25 is an enlarged fragmentary transverse vertical sectional view taken along the line 25—25 of FIGURE 1-A and shows the locking tab in its fully folded position, the locking tab being shown in section and with the uppermost edge portion of the blank ready to be depressed.

FIGURE 26 is an enlarged fragmentary transverse vertical sectional view taken along the line 26—26 of FIGURE 1-A and shows a locking tab of the blank being passed through an associated slit in the opposite edge portion of the blank.

FIGURE 27 is an enlarged fragmentary longitudinal vertical sectional view taken along the line 27—27 of FIGURE 26 and shows the initial positioning of a locking tab in an associated slit in the blank.

FIGURES 28 and 29 are other fragmentary vertical sectional views similar to FIGURE 27 and show further steps in the passing of a locking tab through an associated slit to effect the locking of the locking tab in place.

FIGURE 30 is an enlarged fragmentary transverse vertical sectional view taken along the line 30—30 of FIGURE 1-A and shows the manner in which the locking tab is positively forced through an associated slit.

FIGURE 31 is a plan view of a blank from which the package forming member is folded.

FIGURE 32 is a perspective view showing the completed package formed by the machine.

Referring now to the drawings in detail, reference is first made to FIGURE 32, wherein the completed package formed in accordance with this invention is shown, the package being generally referred to by the numeral 35. The package 35 includes a package forming member 36 which is utilized in coupling together a plurality of members, such as cans C. In order to fully understand the function of the machine, which is the subject of this invention, and the construction of the package forming member 36, reference is now made to the blank, generally referred to by the numeral 37, of FIGURE 31. The blank 37 includes a central panel 38 which is defined in part by C-shaped cut lines 39 and in part by interrupted fold lines 40 which extend between the innermost ends of the C-shaped cut lines 39. Outer fold lines 41 also extend interruptedly between outer portions of the cut lines 39. The fold lines 40 and 41, together with the cut lines 39, define connecting straps 42.

A pair of fold lines 43 disposed outwardly of the fold lines 41 set off intermediate panels 44 which are con-

(FIGURE 1) which guide the blank 37 when carried by the conveyor chains 78.

At the moment a blank 37 becomes aligned with a group of cans C, it is desirable to interlock the blank with the group of cans. This is accomplished by a pair of blank folding blades 96 which form part of an initial blank folding apparatus, generally referred to by the numeral 97. The blank folding apparatus 97 is clearly shown in FIGURES 5 through 13.

In addition to the blank folding blades 96, the blank folding apparatus 97 includes a hanger 98 which is formed of a pair of inverted T-shaped end members 100 connected at the upper ends thereof by means of a transverse bar 101. As is best shown in FIGURE 5, each of the end members 100 carries a pair of pins 102, the pins 102 extending between the two end members 100, as is best shown in FIGURE 5. Each blank folding blade 96 is pivotally mounted on one of the pins 102 by a bracket 103 and a bracket 104. The brackets 104 have upstanding arms 105 which are connected together by a tension spring 106 so as to urge the lower edges of the blank folding blades 96 apart to the positions best shown in FIGURE 8. The outward swinging of the lower edges of the blades 96 is limited by a pair of stop screws 107 which are carried by a transverse bar 108 secured to the end member 100 which is adjacent the fittings 103. The screw stops 107 engage the fittings 103 to restrict the outward swinging movement of the blades 96.

As is best shown in FIGURE 1, the blank folding apparatus 97 is supported from a relatively thick longitudinally extending plate 109 which forms a part of the frame 56. The plate 109 carries for rotation a drive shaft 110 and a pivot shaft 111. A pair of pivot arms 112 suspends from the drive shaft 110 and has the drive shaft 110 rotating through the upper ends thereof. The lower ends of the pivot arms 112 are connected together by a transverse shaft 113. The pivot shaft 111 has a pair of pivot arms 114 adjustably clamped thereto for pivoting therewith. A transverse shaft 115 extends between and connects together the lower ends of the pivot arms 114. The shaft 113 is driven from the drive shaft 110 by a drive chain 119 and sprockets 119a and 119b.

A bar 116 extends between and is carried by the shafts 113 and 115 intermediate the pairs of pivot arms 112 and 114, as is best shown in FIGURE 10. The bar 116 serves to retain the relative positions of the pivot arms 114 with respect to the pivot arms 112. The bar 116 also carries a stub shaft 117 on which an idler gear 118 is rotatably journaled. A pair of gears 120 and 121 is rigidly secured to the shafts 113 and 115, respectively, and is meshed with the idler gear 118 so that when the shaft 113 is rotated in a particular direction at a particular speed, like rotation of the shaft 115 will occur.

A pair of crank arms 122 and 123 is secured to the inner ends of the shafts 113 and 115, respectively. The opposite ends of the crank arms 122 and 123 carry pins 124 and 125 between which a bar 126 is connected for movement. It will be understood that the bar 126 is horizontally disposed at all times, but is moved both vertically and longitudinally of the machine 55.

The bar 126 has a pair of bolts 127 loosely extending therethrough and the lower ends of the bolts 127 are threaded into the bar 101. In this manner, the bar 101 is connected to the bar 126 for movement therewith, although the bar 101 is vertically movable relative to the bar 126. In order to normally hold the bar 101 at a maximum spacing from the bar 126, springs 128 are disposed intermediate the bars 101 and 126.

Although the pivot arms 112 and 114 are free to pivot, during a major portion of the operation of the blank folding apparatus 98, the pivot arms 112 and 114 remain stationary. This is brought about by a spring 129 which is anchored at one end to a bracket 130 carried by the plate 109 and at the opposite end to a pin 131 carried by one of the pivot arms 112. Pivoting of the pivot arms

112 and 114 in a clockwise direction is restricted by a disk 132 which is secured to the drive shaft 110 for rotation, and a cam follower 133. This is best shown in FIGURE 12. The cam follower 133 is carried by an adjustable arm 134 which is adjustably clamped on the shaft 111 for swinging therewith. It is to be understood that the pivot arms 112 and 114 pivot in a counterclockwise direction only when the folding blades 96 move with the blank 37 in a manner to be described in detail hereinafter.

10 Referring now to FIGURE 13 in particular, it will be seen that the disk 132 has been replaced by a cam 135 having a lobe 136 on which the cam follower 133 rides as the pivot arms 112 and 114 swing in a counterclockwise direction. Although the disk 132 will function, when the folding blades 96 are released from a blank during the blank folding operation, the spring 129 slams the cam follower 133 back into engagement with the disk 132. This slamming action of the spring 129 is eliminated utilizing the cam 135.

15 Referring once again to FIGURE 8, it will be seen that as the folding blades 96 come down into engagement with a blank 37, the folding blades 96 are spaced apart a considerable distance and are disposed just inwardly of the blank supports 90. It is to be understood that the lower edges of the folding blades 96 will engage the blank 37 generally along the fold lines 43 thereof. After the folding blade 96 engages the blank 37 and continues to move downwardly, the blank 37 folds generally along the fold lines 43 and the central panel 38 thereof is brought to bear against the top of the cans C. Further downward movement of the folding blades 96 results in the inward swinging of the lower edges thereof and with the intermediate panels 44 and 46 on one side of the cans and intermediate panels 44 and 49 on the opposite sides 25 of the cans being generally reverse folded by the downward movement of the folding blades 96 between the cans C and the blank supports 90. As a result, the inner intermediate panels 44 are brought to bear against the sides of the cans C and the seams S thereof, which define peripheral projections, are forced through the openings defined by the C-shaped cuts 39 to interlock the upper ends of the cans C with the central portion of the blank 37. It is to be noted that the connecting straps 42 are diagonally disposed at this time.

30 40 45 It is pointed out that during the initial folding of the blank 37 around the top of a can C, the cans C continue to move. However, movement of the blank 37 is not retarded by the stops 88 in that as soon as the blank 37 starts to pivot about the blank support 90, as is generally shown in FIGURE 9, the leading edge of the blank 37 moves up above the plane of the stops 88 and the blank 37 is free to continue to move with the group of cans to which it is being applied. As is clearly shown in the two views of FIGURES 6 and 7, the folding blades 96

50 55 55 move with the blank 37 during the attachment of the blank 37 to the upper ends of the cans C. Thus, the blank folding operation is brought about without stopping the motion of the blank or the cans to which it is being connected. At this time, it is deemed advisable to disclose the details of the drive means of the machine

nected to the central panel 38 by the connecting straps 42. A fold line 45 combines with one of the fold lines 43 to define a first outer intermediate panel 46. Another fold line 47, which is interrupted by generally C-shaped cut lines 48, combines with the other of the fold line 43 to define a second outer intermediate panel 49. The cut lines 48 simultaneously define tabs 50 and slits 51, the slits 51 being best shown in FIGURE 21, for example. The blank 37 outwardly of the fold line 47 is in the form of an outer panel 52.

The blank 37 outwardly of the fold line 45 is in the form of a second outer panel 53. The outer panel 53 has a plurality of locking tabs 54 projecting therefrom, the locking tabs 54 corresponding in positions to the cut lines 48 and being adapted to pass through the slits 51 in a manner to be shown hereinafter.

Referring now to FIGURES 1 and 2, it will be seen that there are illustrated portions of the machine which is the subject of this invention, the machine being generally referred to by the numeral 55. The machine 55 includes a suitable frame, generally referred to by the numeral 56, which supports the various components of the machine 55. The left end of the frame 56 carries a pair of parallel can guides 57 which engage upper portions of cans C and maintain the cans C in a straight line. The cans C are moved between the guides 57 by means of a pair of endless conveyor chains 58 on which the cans C are seated. This is best shown in FIGURE 2, wherein the cans C are illustrated as being seated on the upper runs of the endless conveyor chains 58. It is to be noted that the endless conveyor chain upper runs are supported intermediate the ends thereof by a transverse plate 60. Others of these plates may be provided at spaced intervals, if desired. The right ends of the conveyor chains 58 are carried by drive sprockets 61 which are mounted on a drive shaft 62. The left ends of the conveyor chains 58 are engaged around suitable idler sprockets 59. It is to be also understood that cans C will be delivered to the conveyor chains 58 on a continuous basis so that a continuous line of cans C, such as that shown in FIGURES 1 and 2 will be available.

The first operation of the machine 55 in the forming of a package 35 is to supply blanks to the cans C and to separate the cans into longitudinally spaced groups, with each group of cans including a predetermined number of cans. Reference is now made to FIGURES 1 and 1-A, wherein it will be seen that a pair of conveyor chains 63 are provided for receiving cans C from the conveyor chains 58 and for arranging the cans in groups. In accordance with the package forming member 36, each group of cans should contain four cans C.

The conveyor chains 63 include a pair of opposed runs 64 which are disposed on opposite sides of the path of movement of the cans C. In defining the opposed runs 64, the chains 63 pass around idler sprockets 65 and 66 at opposite ends of the runs 64. Each conveyor chain 63 passes to the run 64 around a drive sprocket 67 and then to the idler sprocket 65. Prior to passing around the associated drive sprocket 67, each conveyor chain 63 passes around another drive sprocket 68, the drive sprocket 68 being generally longitudinally aligned with intermediate idler sprocket 69, as is best shown in FIGURE 1-A.

One of the conveyor chains 63 is provided with a plurality of pusher elements 70 which in the illustrated form of the invention are spaced apart two cans. Each of the pusher elements 70 has a generally triangular outline and is contoured so as to fit in between a pair of immediately adjacent cans and serve to push the cans disposed in a line. The pusher elements 70 also combine to hold the cans in alignment between the chains. The other of the conveyor chains 63 is provided with alternating pusher elements 71 and 72. The pusher elements 71 are identical with the pusher elements 70 and serve the same purpose. On the other hand, the pusher elements 72 are provided

with rounded end portions 73 adapted to be forced between adjacent cans in a line of cans and to separate the cans of one group from the cans of another group. It is to be noted that the pusher elements 70 are disposed out of phase with the pusher elements 71 and 72 so that each can in a group of cans is engaged by one of the pusher elements 70, 71 or 72.

After the cans C have been separated into groups of four cans each, it is necessary to position one of the blanks 37 with respect to each group of cans. Reference is accordingly made to FIGURE 2-B wherein it is shown that the blanks 37 are stored in a hopper 74 and are retained therein by means of spring fingers 75. An arm 76 is mounted beneath the hopper 75 for pivotal movement and is provided at the free end thereof with a suction cup 77 for engaging the lowermost blank 37 in the hopper 74 and for retracting the same against the holding power of the spring fingers 75. It is to be understood that the arm 76 is pivoted in timed relation to the operation of the machine 55 in a conventional manner not described here.

A pair of spaced apart endless conveyor chains 78 extend beneath the hopper 74 on opposite sides of the path of the cans C and with the upper runs thereof disposed for receiving a blank 37 from the arm 76 and the suction cup 77 carried thereby. As the arm 76 moves down between the top runs of the conveyor chains 78, the blank 37 carried by the suction cup 77 is pulled therefrom. The blanks 37 are slid off of the suction cup 77 by means of dogs 80 spaced along the conveyor chains 78, the dogs 80 being disposed in transverse alignment.

At this time, it is to be pointed out that the conveyor chains 78 are supported at the left ends thereof by means of drive sprockets 81 which are mounted on a transverse drive shaft 82 for rotation. The opposite ends of the conveyor chains 78 are entrained around idler sprockets 83 which are carried by stub shafts 84. Intermediate portions of the top runs of each conveyor chain 78 are supported by one or more plates 85, as is best shown in FIGURE 2.

Referring now to FIGURE 5 in particular, it will be seen that as the blanks 37 pass off of the conveyor chains 78, the leading ends thereof will strike against downwardly sloping guides 86 so as to direct the leading ends of the blanks 37 down onto the tops of the group of cans C to which the blank 37 is to be connected in a package forming operation. As the trailing edge of each blank 37 leaves the conveyor chains 78, the trailing edge engages spaced apart guides 87 so as to advance the blank 37 independently of the motion transmitted thereto by the conveyor chains 78 so that the forward edge of each blank 37 comes into engagement with a pair of transversely spaced stops 88 in timed relation to the movement of a group of cans C therebeneath. A transversely extending, curved guide 89 associated with the stops 88 assures the engagement of each blank 37 with the stops 88.

Reference is now made to FIGURE 8 wherein it will be seen that the blank 37 does not drop onto the cans C, but is initially supported in overlying relation with respect to the cans C by a pair of blank supports 90 which extend longitudinally of the machine 55 on opposite sides of the path of movement of the cans C.

Referring once again to FIGURE 8, it will be seen that at the time the blank 37 is delivered into overlying relation to a group of cans C, the cans are supported on a horizontal plate 91 which forms a part of the frame 56 of the machine. Suitable supports 92 extend upwardly from the plate 91 and support guides 93 for the inner runs 64 of the conveyor chains 63. The guides 93 also serve to support the blank supports 90 and the stops 88. It is also to be noted that a pair of upstanding guide plates 94 are carried by the plate 91 and serve as guides for the blank 37 so as to assure transverse alignment of the blanks 37 with a group of cans. The blank guides 94 are disposed in alignment with other blank guides 95

Referring once again to FIGURE 4, it will be seen that the side plates 140 have a horizontal plate 143 extending therebetween. The horizontal plate 143 supports suitable bearing holders for the shafts which, in turn, carry the various sprockets for the conveyor chains 63. In FIGURE 4, it is illustrated that the sprockets 63 are carried by vertical shafts 149 which are rotatably journaled in bearing supports 150 and which are provided at the lower ends thereof with bevel bears 151 which are meshed with and driven by bevel gears 152 carried by 10 th main drive shaft 137.

The sprockets 67 are carried by vertical shafts 153 which are rotatably journaled in bearing supports 154 mounted on the plate 143. Each shaft 153 is provided with a sprocket 155 which is aligned with a sprocket 156 15 carried by an associated shaft 149. Adjacent ones of the sprockets 155 and 156 are connected together by a chain 157 so that the sprockets 67 are driven from the shafts 149.

It is to be noted that a pair of plates 158 extends upwardly from central portions of the plate 143. The plates 158 are disposed on opposite sides of the path of cans C and extend longitudinally of the machine 55. The plates 158 carry bearings 160 in which the shaft 62 is rotatably journaled. The shaft 62 is driven from the drive shaft 137 by means of a sprocket 161 on the drive shaft 137 and a sprocket 162 on the shaft 60. A drive chain 163 is entrained over the sprockets 161 and 162.

At this time, it is pointed out that in addition to being supported by the conveyor chains 78, the blank 37 being conveyed by the conveyor chains 78 is also supported by a pair of outer supports 164. The supports 164 are carried by the guide plates 95, as is clearly shown in FIGURE 4.

It is to be noted that the blank conveyor chains 78 and the folding apparatus 98 are both driven from the drive sprocket 142 by means of a drive chain 165. A stub shaft 166 is rotatably carried by one of the side plates 140 and is provided on one end thereof with a large diameter sprocket 167 and on the opposite end thereof with a small diameter sprocket 168. The drive shaft 82 is provided with a sprocket 169.

As is best shown in FIGURES 2 and 3, the drive chain 165 passes upwardly from the drive sprocket 142 over an idler sprocket 170 which is carried by a stub shaft 171 supported by one of the side plates 140. The drive chain 165 then passes around the sprocket 169 and is returned beneath the sprocket 167. The drive chain 165 extends upwardly around the sprocket 167 around an idler sprocket 172 which, in turn, is carried by a stub shaft 173 also suitably supported by the one side plate 140.

Referring once again to FIGURE 3 in particular, it will be seen that the shaft 110 is driven from the shaft 166. The other end of the shaft 110 is provided with a sprocket 174 which is vertically aligned with the sprocket 168 carried by the shaft 166. A drive chain 170 is entrained over the sprockets 168 and 174.

At this time, it is pointed out that all of the components of the machine 55 are driven so as to be in timed relation with one another. The proportions shown in FIGURE 3 are generally correct.

Referring now to FIGURE 21 in particular, it will be seen that a pair of folding members 176 and 178 extend generally as continuations of the blank supports 90. As is clearly shown in FIGURE 1-A, the folding member 176 has a tapered leading edge 177 while the folding member 178 has a tapered leading edge 180. As the group of cans C, together with the blank 37 interlocked therewith, moves longitudinally along the machine 55, the partially folded intermediate panels 44, 46 and 49 of the blank 37 are folded into reversely folded relation by the folding members 176 and 178 in the manner generally shown in FIGURE 21. The action of the folding members 176 and 178 also serves to swing the outer panels 52 and 53 of the blank 37 generally into overlying relation with respect

to the central panels 38 and with the panel 52 being disposed inwardly of the panel 53.

The folding member 178 carries a bracket 181 which, in turn, carries a folding wheel 182 which engages the panel 52 and urges the same inwardly into overlying relation with respect to the central panel 38, as is shown in FIGURE 21. The folding member also supports a folding wheel 183 which is disposed lower than the folding wheel 182 and thus effects a greater inward folding of the outer panel 52, as is shown in FIGURE 23.

The folding member 176 carries a support plate 184 which, in turn, carries a plurality of rollers 185. The axes of the rollers 185 slope toward the center of the machine 55, as is clearly shown in FIGURE 1-A, and progressively fold the outer panel 53 inwardly into overlying relation to the outer panel 52.

Referring now to FIGURE 20 in particular, it will be seen that there is illustrated a folding blade assembly, generally referred to by the numeral 186. The folding blade assembly 186 includes a flat folding blade 187 and an angular folding blade 188. The flat folding blade 187 has a downwardly and rearwardly sloping upper surface 189 and a downwardly and more severely rearwardly sloping lower forward edge 190. The blade 187 also includes a lower rear edge 191.

The blade 188 includes a vertical leg 192 and a horizontal leg 193. The vertical leg 192 includes a downwardly and rearwardly sloping forward edge 194 and horizontal lower edge 195. The height of the blade portion 192 decreases from left to right, as viewed in FIGURE 20, so that the horizontal leg 193 slopes downwardly and rearwardly parallel to the upper edge 189 of the blade 187.

The blades 187 and 188 are connected together by a pair of fasteners 196 which pass through the blade 187 and the vertical leg 192, with the blade 187 being spaced from the vertical leg 192 by means of spacers 197 carried by the fasteners 196. The fasteners 196 are threaded into the mounting block 198 which serves to support the folding blade assembly 186 in angular relation to the longitudinal axis of the machine 55 and from the folding member 178, as is best shown in FIGURE 1-A. It is to be noted that the mounting block 198 is slotted so that it may be angularly adjusted.

Referring now to FIGURE 22 in particular, it will be seen that the folding wheels 185 drive the panel 53 of the blank 37 so that it passes between the projecting portions of the folding blades 187 and the folding blade leg 193 with the outer edge of the panel 53 being disposed generally between the folding blade 187 and the folding blade leg 193.

Referring now to FIGURES 15 and 16, it will be seen that a locking tab 54 of the blank 37 first engages a tapered leading edge 200 of the horizontal leg 193 so that the locking tab 54 is guided to the right, as viewed in FIGURE 22, and positioning of a locking tab 54 extending from between the folding blade 187 and the folding blade leg 193 is assured.

As the locking tab 54 continues to move with respect to the folding blade assembly 186, the folding blade leg 193 moves into overlying relation with respect to the folding blade 187, as is clearly shown in FIGURES 17 and 23, and the locking tab 54 assumes a horizontal position. Further movement of the locking tab 54 with respect to the folding blade assembly 186 results in the engagement of the locking tab 54 with the sloping leading edge 194 of the vertical leg 192 to effect a downward turning of the locking tab 54 in the manner best shown in FIGURE 18. After the locking tab 54 has been turned downwardly, it assumes the position shown in FIGURE 24 and then is progressively moved downwardly towards the panel 52 of the blank 37 due to the downward movement of the horizontal leg 193. At the same time, the lower edge 191 of the folding blade 187 is holding down the panel 52, the panel 52 having been urged downwardly

11

by engagement thereof with the leading edge 190 of the folding blade 187.

It is to be understood that as the locking tabs 54 progressively approach the folding blade assembly 186, the folding action is repeated with respect thereto, as is clearly shown in FIGURE 19. It is further to be noted that as the locking tabs 54 are folded over, the panel 53 is progressively moved downwardly towards the panel 52 in overlying relation thereto.

As the carton blank begins to move out of engagement with the folding blade assembly 186, the panel 53 comes into engagement with the underside of a presser foot 201 which is centrally located and which is provided with a tapered leading edge 202, as is best shown in FIGURE 2-A, which leading edge 202 generally overlaps the folding blade assembly 186.

Referring now to FIGURE 1-A, it will be seen that the presser foot 201 is supported from a bracket 203 which is mounted on the folding member 176. Suitable spacers 204 space the presser foot 201 from the bracket 203.

The folding member 178 carries a guide 205 which is angular in cross-section, as is best shown in FIGURE 26. The guide 205 includes a vertical surface 206 against which each locking tab 54 bears so as to assure the alignment of the locking tabs 54 with the slits 51 formed in the panels 52. As the panel 53 rides under the presser foot 201, as is shown in FIGURE 26, the locking tabs 54 are urged down through the slits 51 in a manner best shown in FIGURES 27, 28 and 29.

It is to be noted that each locking tab 54 is provided with a pair of ears 207 which lock behind the panel 52 to provide a permanent interlock between the panels 52 and 53 when the locking tabs are firmly seated, as is shown in FIGURE 29.

The final seating of the locking tabs 54 through the panel 52 is assured by a plurality of presser wheels 208. Each presser wheel 208 has a generally frusto-conical surface 209 which bears against the upper surface of the panel 53 to assure the downward movement of the associated locking tabs 54. Each wheel 208 is carried by a stub axle 210 and the stub axles 210 are carried by a mounting bracket 211 which is suitably mounted on the folding member 178, as is clearly shown in FIGURES 1-A and 30.

After the locking tabs 54 have been passed through the panel 52, the formation of the package 35 is complete and the cans C are firmly interlocked with the package forming member 36 in a manner whereby the cans can be removed only by tearing them out of the package forming member 36 and rupturing the package forming member. The completed packages 35 are then delivered onto a take-away conveyor 212 which is mounted at the right end of the machine 55, as is clearly shown in FIGURES 1-A and 2-A.

Operation

In accordance with the invention, in the operation of the machine 55, a plurality of members to be packaged are continuously delivered to the machine 55 by the conveyor chains 58 so as to continuously supply the members at all times and in the supply of the members, the members are in contiguous relation. These members, which are principally cans, are then engaged by the conveyor chains 63 and separated into spaced groups of a predetermined number. Simultaneous with the feeding of the cans C by the endless chains 63 and the separation thereof into groups, blanks 37 are delivered into overlying relation to the cans C by means of conveyor chains 78.

The blank 37 is brought to bear against a pair of spaced stops 88 and simultaneously into overlying relation with respect to a group of cans C, as is generally shown in FIGURE 8. The blank immediately thereafter is downwardly folded by means of the folding

12

blades 96 to the position shown in FIGURES 9 and 9-A, with the blank 37 being drawn away from the stops 88 and thereby instantaneously released. It is to be understood that there is no stopping of the movement of the cans C during the application of the blank thereto in the manner shown in FIGURE 9-A.

As the partially assembled blank and the group of cans move along the machine 55, the partially reversely folded lower portions of the blank are completely reversely folded by engagement with the folding members 176 and 178 so that on one side of the cans C, the panel 44 of the blank is engaged with the panel 46, and on the opposite sides of the cans, the corresponding panel 44 is engaged with the panel 49. The outer panels 52 and 53, which may be considered flaps, are momentarily vertically disposed, after which they are folded inwardly to overlying relation with respect to the central panel 38 of the blank by means of the folding wheels 182, 183 and 185.

After the panels 52 and 53 have been folded to the positions generally illustrated in FIGURE 21, the locking tabs 54 of the panel 53 are engaged by the folding blade assembly 186 and continued folding of the panels 52 and 53 results, while the locking tabs 54 are folded relative to the associated panel 53, as is shown in FIGURE 23. The folding blade assembly 186 continues to fold the locking tabs 54 and at the same time continue to inwardly fold the panels 52 and 53, as is shown in FIGURES 24 and 25.

After the locking tabs 54 have been completely folded with respect to the panel 53 and are brought into engagement with a guide 205, as is shown in FIGURE 26, the central portion of the panel 53 is engaged by a presser foot 201 which urges the same downwardly and forces the locking tabs 54 through the slots 51 formed in the panel 52. The locking tabs 54 are finally seated by the wheels 208 in the manner shown in FIGURE 30.

From the foregoing, it will be readily apparent that there has been devised a machine which will automatically receive a plurality of like elements, such as cans, separate the cans into groups of a predetermined number, apply a blank to the cans, interlock the blank with the cans, and then fold and lock together the blank to define a package forming member which is interlocked with the cans to define the package 35, which is the intended product of the machine. No manual operation is required.

Although only a preferred embodiment of the machine has been illustrated and described herein, it is to be understood that minor variations may be made therein without departing from the spirit and scope of the invention, as defined in the appended claims.

I claim:

1. An apparatus for forming a package of the type including a plurality of members disposed in a row and having one end only thereof positioned in and interlocked with a package forming member, said apparatus comprising a conveyor for moving members to be packaged in groups of a predetermined number, blank feed means for depositing a blank in overlying aligned relation to each group of members, first fold means for reversely folding intermediate portions of each blank down alongside each group of members with a central portion of each blank directly overlying the members, second fold means for inwardly folding blank edge portions into lapped relation overlying the blank central portion, and means for effecting the interlocking of edge portions of each blank to complete the packages.

2. An apparatus for forming a package of the type including a plurality of members each having a peripheral projection at one end thereof and with the members being disposed in a row with the one ends positioned in and interlocked with a package forming member which is provided in the form of a blank having a central portion

with a row of notches on each side thereof, said apparatus comprising a conveyor for moving members to be packaged in groups of a predetermined number and with the one ends thereof uppermost, blank feed means for depositing a blank in overlying relation to each group of members, first fold means engageable with a blank on opposite sides of the group of members and urging intermediate portions of the blank downwardly around the members and firmly seating the central portion of the blank on the upper ends of the members with the projections of the members being seated in notches of the blank, second fold means for engaging outer portions of a blank and folding the outer portions upwardly and inwardly towards the members to define reversely folded intermediate portions of the blank on each side of the group of members, third fold means for inwardly folding blank edge portions into lapped relation overlying the blank central portion, and means for effecting the interlocking of edge portions of each blank to complete the packages.

3. An apparatus for forming a package of the type including a plurality of members each having a peripheral projection at one end thereof and with the members being disposed in a row with the one ends positioned in and interlocked with a package forming member which is provided in the form of a blank having a central portion with a row of notches on each side thereof and one edge terminating in locking tabs while the opposite edge portion has tab receiving slits, said apparatus comprising a conveyor for moving members to be packaged in groups of a predetermined number and with the one ends thereof uppermost, blank feed means for depositing a blank in overlying relation to each group of members, first fold means engageable with a blank on opposite sides of the group of members and urging intermediate portions of the blank downwardly around the members and firmly seating the central portion of the blank on the upper ends of the members with the projections of the members being seated in notches of the blank, second fold means for engaging outer portions of a blank and folding the outer portions upwardly and inwardly towards the members to define reversely folded intermediate portions of the blank on each side of the group of members, third folding means for inwardly folding the blank edge portions into lapped relation overlying the blank central portion, and means for effecting the seating of the locking tabs in the tab receiving slits to effect the interlocking of the edge portions of each blank to complete the package.

4. In an apparatus for applying blanks to moving groups of members having annular projections at the upper ends thereof to form packages, and wherein each blank has a central portion with a row of notches along each side thereof, apparatus for seating a blank on each group of members comprising a pair of spaced blank supports, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank, and folding members having converging opposed faces engageable by the reversely folded intermediate portion to flatten the intermediate portions against the opposite sides of the members.

5. The apparatus of claim 4 wherein said blade support means includes a hanger, means pivotally connecting said blades to opposite sides of said hanger, spring means connected to said blades urging lower edges of said blades apart, and stop means carried by said hanger limiting the swinging apart of said blades.

6. The apparatus of claim 4 wherein said blade support means includes a hanger, linkage supporting said hanger, and means for pivoting said linkage to impart

both a vertical and a longitudinal movement to said hanger.

7. The apparatus of claim 4 wherein said blade support means includes a hanger, a bar above said hanger, a pair of rotating links carried by said bar, a pair of pivotally mounted links connected to said rotating links, and drive means connected to said rotating links for effecting the rotation thereof to reciprocate said hanger both vertically and longitudinally.

10 8. The apparatus of claim 4 wherein said blade support means includes a hanger, a bar above said hanger, a pair of rotating links carried by said bar, a pair of pivotally mounted links connected to said rotating links, drive means connected to said rotating links for effecting the 15 rotation thereof to reciprocate said hanger both vertically and longitudinally, spring means restricting swinging of said pivotally mounted links in the direction of member movement, and means limiting movement of said pivotally mounted links by said spring means.

9. The apparatus of claim 4 wherein said blade support means includes a hanger, a bar above said hanger, a pair of rotating links carried by said bar, a pair of pivotally mounted links connected to said rotating links, drive means connected to said rotating links for effecting the 25 rotation thereof to reciprocate said hanger both vertically and longitudinally, and cam means connected to said pivotally mounted links for controlling the pivoting of said pivotally mounted links in timed relation to the rotation of said rotating links.

30 10. The apparatus of claim 4 wherein said blade support means includes a hanger, a bar above said hanger, a pair of rotating links carried by said bar, a pair of pivotally mounted links connected to said rotating links, drive means connected to said rotating links for effecting the 35 rotation thereof to reciprocate said hanger both vertically and longitudinally, and a resilient take-up connection between said bar and said hanger.

11. In an apparatus for applying blanks to moving groups of members having annular projections at the upper ends thereof to form packages, and wherein each blank has a central portion with a row of notches along each side thereof, apparatus for seating a blank on each group of members comprising a pair of spaced blank supports, and a pair of blank folding blades, means supporting said blades for vertical movement down alongside the group of members intermediate said blank supports to seat the blank central portion on upper ends of the members and engaging the member projections in the blank notches to interlock the blank and the members 40 while downwardly reversely folding intermediate portions of the blank, said blade support means including a hanger, means pivotally connecting said blades to opposite sides of said hanger, spring means connected to said blades urging lower edges of said blades apart, and stop means carried by said hanger limiting the swinging apart of said blades.

12. In an apparatus for applying blanks to moving groups of members having annular projections at the upper ends thereof to form packages, and wherein each blank has a central portion with a row of notches along each side thereof, apparatus for seating a blank on each group of members comprising a pair of spaced blank supports, and a pair of blank folding blades, means supporting said blades for vertical movement down alongside the group of members intermediate said blank supports to seat the blank central portion on upper ends of the members and engaging the member projections in the blank notches to interlock the blank and the members 50 while downwardly reversely folding intermediate portions of the blank, said blade support means including a hanger, a bar above said hanger, a pair of rotating links carried by said bar, a pair of pivotally mounted links connected to said rotating links, and drive means connected to said rotating links for effecting the rotation thereof to reciprocate said hanger both vertically and longitudinally.

60 65 70 75 13. In an apparatus for applying blanks to moving groups of members having annular projections at the upper ends thereof to form packages, and wherein each blank has a central portion with a row of notches along each side thereof, apparatus for seating a blank on each group of members comprising a pair of spaced blank supports, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank, said blade support means including a hanger, a bar above said hanger, a pair of rotating links carried by said bar, a pair of pivotally mounted links connected to said rotating links, and drive means connected to said rotating links for effecting the rotation thereof to reciprocate said hanger both vertically and longitudinally.

13. In a package forming apparatus particularly adapted to assemble and position a moving package forming member having overlapping edge portions with one edge portion having terminal projecting locking tabs and the other edge portion having locking tab receiving slits, means for progressively bringing the edge portions into overlapping relation, and coextensive locking tab folding means for progressively folding the locking tabs out of the plane of the one edge portion and into alignment with the slits in the other edge portion, said locking tab folding means including first and second tab folding blades, said first tab folding blade being disposed generally normal to the final plane of the edge portions, and said second tab folding blade including a first portion normal to said first tab folding blade and cooperating therewith to effect an initial folding of locking tabs, and a second portion disposed parallel to said first tab folding blade for finally folding locking tabs.

14. The apparatus of claim 13 wherein said tab folding blades extend in the direction of movement of package forming members and slope away from the connection between the one edge portion and the remainder of the packaging member to compensate for the folding of the one edge portion.

15. The apparatus of claim 14 wherein the tab folding blades also slope towards the final plane of the edge portions.

16. In an apparatus for applying blanks to moving groups of members having annular projections at the upper ends thereof to form packages, and wherein each blank has a central portion with a row of notches along each side thereof, apparatus for seating a blank on each group of members comprising a pair of spaced blank supports, means for feeding blanks onto said blank supports in timed relation to the movement of groups of members therebeneath, fixed stop members carried by said blank supports for momentarily fixedly positioning blanks to assure the alignment thereof with groups of members, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank.

17. In an apparatus for applying blanks to moving groups of members having annular projections at the upper ends thereof to form packages, and wherein each blank has a central portion with a row of notches along each side thereof, apparatus for seating a blank on each group of members comprising a pair of spaced blank supports, means for feeding blanks onto said blank supports in timed relation to the movement of groups of members therebeneath, fixed stop members carried by said blank supports for momentarily fixedly positioning blanks to assure the alignment thereof with groups of members, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank, and folding members having converging opposed faces engageable by the reversely folded intermediate portion to flatten the intermediate portions against the opposite sides of the members.

18. In a can packaging apparatus wherein a continuous supply of cans in a single row is provided, conveyor means for moving cans in spaced groups along a predetermined path, said conveyor means including an endless member having a first run extending at an angle to the row of can bodies and a second run extending parallel to the path of movement of the can bodies, pusher elements carried by said endless member for separating the

cans into groups, said pusher elements each having an enlarged rounded end facilitating the entry thereof in between adjacent cans and serving as a spacer between adjacent groups of cans, additional pusher elements carried by said endless member intermediate the first mentioned pusher elements and contoured for engaging intermediate cans between the first mentioned pusher elements, a second endless member having a run parallel to and opposing the second run of the first mentioned endless member, and pusher elements carried by said second endless member generally opposing the pusher elements of the first mentioned endless member and being staggered relative thereto.

19. In an apparatus for applying blanks to moving groups of members having annular projections at the upper ends thereof to form packages, and wherein each blank has a central portion with a row of notches along each side thereof, apparatus for seating a blank on each group of members comprising means for providing a continuous supply of the members in a single row, conveyor means for dividing members into spaced groups and moving the groups along a predetermined path, said conveyor means including an endless member having a first run extending at an angle to the path of movement of the members and a second run extending parallel to the path of movement of the members, pusher elements carried by said endless member for separating the members into groups, said pusher elements each having an enlarged rounded end facilitating the entry thereof in between adjacent members and serving as a spacer between adjacent groups of members, a pair of spaced blank supports, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank.

20. In an apparatus for applying blanks to moving groups of members having annular projections at the upper ends thereof to form packages, and wherein each blank has a central portion with a row of notches along each side thereof, apparatus for seating a blank on each group of members comprising means for providing a continuous supply of the members in a single row, conveyor means for dividing members into spaced groups and moving the groups along a predetermined path, said conveyor means including an endless member having a first run extending at an angle to the path of movement of the members and a second run extending parallel to the path of movement of the members, pusher elements carried by said endless member for separating the members into groups, said pusher elements each having an enlarged rounded end facilitating the entry thereof in between adjacent members and serving as a spacer between adjacent groups of members, a pair of spaced blank supports, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank, and folding members having converging opposed faces engageable by the reversely folded intermediate portion to flatten the intermediate portions against the opposite sides of the members.

21. In an apparatus for applying blanks to moving groups of members having annular projections at the upper ends thereof to form packages, and wherein each blank has a central portion with a row of notches along each side thereof, apparatus for seating a blank on each group of members comprising means for providing a continuous supply of the members in a single row, conveyor means for dividing members into spaced groups and moving the

groups along a predetermined path, said conveyor means including an endless member having a first run extending at an angle to the path of movement of the members and a second run extending parallel to the path of movement of the members, pusher elements carried by said endless member for separating the members into groups, said pusher elements each having an enlarged rounded end facilitating the entry thereof in between adjacent members and serving as a spacer between adjacent groups of members, a pair of spaced blank supports, means for feeding blanks onto said blank supports in timed relation to the movement of groups of members therebeneath, fixed stop members carried by said blank supports for momentarily fixedly positioning blanks to assure the alignment thereof with groups of members, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank.

22. In an apparatus for applying blanks to moving groups of members having annular projections at the upper ends thereof to form packages, and wherein each blank has a central portion with a row of notches along each side thereof, apparatus for seating a blank on each group of members comprising means for providing a continuous supply of the members in a single row, conveyor means for dividing members into spaced groups and moving the groups along a predetermined path, said conveyor means including an endless member having a first run extending at an angle to the path of movement of the members and a second run extending parallel to the path of movement of the members, pusher elements carried by said endless member for separating the members into groups, said pusher elements each having an enlarged rounded end facilitating the entry thereof in between adjacent members and serving as a spacer between adjacent groups of members, a pair of spaced blank supports, means for feeding blanks onto said blank supports in timed relation to the movement of groups of members therebeneath, fixed stop members carried by said blank supports for momentarily fixedly positioning blanks to assure the alignment thereof with groups of members, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank, and folding members having converging opposed faces engageable by the reversely folded intermediate portion to flatten the intermediate portions against the opposite sides of the members.

23. In an apparatus for applying blanks to moving groups of members having annular projections at the upper ends thereof to form packages, and wherein each blank has a central portion with a row of notches along each side thereof, and one edge terminating in projecting coplanar locking tabs while the opposite edge portion has the tab receiving slits, apparatus for seating a blank on each group of members comprising a pair of spaced blank supports, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank, and folding members having converging opposed faces engageable by the reversely folded intermediate portion to flatten the intermediate portions

against the opposite sides of the members, folding means for inwardly folding the blank edge portions into lapped relation overlying the blank central portion, and means for effecting the seating of the locking tabs in the tab receiving slits to effect the interlocking of the edge portions of each blank to complete the package.

24. The apparatus of claim 23 together with locking tab folding means including first and second tab folding blades, said first tab folding blade being disposed generally normal to the final plane of the edge portions, and said second tab folding blade including a first portion normal to said first tab folding blade and cooperating therewith to effect an initial folding of locking tabs, and a second portion disposed parallel to said first tab folding blade for finally folding locking tabs.

25. The apparatus of claim 24 wherein said tab folding blades extend in the direction of movement of package forming members and slope away from the connection between the one edge portion and the remainder of the packaging member to compensate for the folding of the one edge portion.

26. In an apparatus for applying blanks to moving groups of members having annular projections at the upper ends thereof to form packages, and wherein each blank has a central portion with a row of notches along each side thereof, and one edge terminating in projecting coplanar locking tabs while the opposite edge portion has the tab receiving slits, apparatus for seating a blank on each group of members comprising a pair of spaced blank supports, means for feeding blanks onto said blank supports in timed relation to the movement of groups of members therebeneath, fixed stop members carried by said blank supports for momentarily fixedly positioning blanks to assure the alignment thereof with groups of members, and a pair of blank folding blades, means supporting said blades for vertical movement down alongside the group of members intermediate said blank supports to seat the blank central portion on upper ends of the members and engaging the member projections in the blank notches to interlock the blank and the members while downwardly reversely folding intermediate portions of the blank, and folding members having converging opposed faces engageable by the reversely folded intermediate portion to flatten the intermediate portions against the opposite sides of the members, folding means for inwardly folding the blank edge portions into lapped relation overlying the blank central portion, and means for effecting the seating of the locking tabs in the tab receiving slits to effect the interlocking of the edge portions of each blank to complete the package.

27. In an apparatus for applying blanks to moving groups of members having annular projections at the upper ends thereof to form packages, and wherein each blank has a central portion with a row of notches along each side thereof, and one edge terminating in projecting coplanar locking tabs while the opposite edge portion has the tab receiving slits, apparatus for seating a blank on each group of members comprising means for providing a continuous supply of the members in a single row, conveyor means for dividing members into spaced groups and moving the groups along a predetermined path, said conveyor means including an endless member having a first run extending at an angle to the path of movement of the members and a second run extending parallel to the path of movement of the members, pusher elements carried by said endless member for separating the members into groups, said pusher elements each having an enlarged rounded end facilitating the entry thereof in between adjacent members and serving as a spacer between adjacent groups of members, a pair of spaced blank supports, and a pair of blank folding blades, means supporting said blades for vertical movement down alongside the group of members intermediate said blank supports to seat the blank central portion on upper ends

of the members and engaging the member projections in the blank notches to interlock the blank and the members while downwardly reversely folding intermediate portions of the blank, and folding members having converging opposed faces engageable by the reversely folded intermediate portion to flatten the intermediate portions against the opposite sides of the members, folding means for inwardly folding the blank edge portions into lapped relation overlying the blank central portions, and means for effecting the seating of the locking tabs in the tab receiving slits to effect the interlocking of the edge portions of each blank to complete the package.
